DYEING WITH QUINONES OR HYDROQUINONES AND BOROHYDRIDES AND COMPOSITIONS THEREFOR

Raymond Stanley Max Frohnsdorff, Twickenham, and John Upton Lewin, Isleworth, England, assignors to The Gillette Company, Boston, Mass., a corporation of Delaware

No Drawing. Application October 6, 1954,
Serial No. 460,776

Claims priority, application Great Britain April 30, 1954

8 Claims. (Cl. 167—83)

This invention is for improvements in or relating to the production and/or stabilization of hydroquinones and has for an object to provide stabilized solutions of hydroquinones which, *inter alia*, may be useful for the preparation of solutions for the dyeing and tinting of hair.

Many substances useful in the dyeing and tinting of hair are quinone compounds of the benzene and naphthalene series, but many of these quinones are either themselves unstable or are insufficiently soluble in water to allow the preparation of solutions of a high enough concentration to provide an effective dyeing solution.

For example, the natural dyes contained in henna have to be applied to the hair by padding, which involves preparing a moistened mass of the natural henna-containing vegetable material and applying it directly to the hair.

The present invention makes it possible readily to reduce such difficulty soluble quinones to the more soluble hydroquinones, thus making it possible to prepare dyeing and tinting solutions of much higher concentration than is possible with the natural product.

According to the present invention, therefore, there is provided a process for the reduction of quinones and/or the stabilization of hydroquinones which comprises treating the quinones or hydroquinones with an aqueous alkaline solution of an alkali metal borohydride such as sodium or potassium borohydride. The borohydrides may generally be employed for reducing and solubilizing the oxidized form of oxidative dyestuffs such as vat dyes which form leuco-compounds, as well as for stabilizing aqueous solutions of the reduced or leuco-form of the dye. The invention also includes stabilized solutions of hydroquinone comprising an aqueous alkaline solution containing the hydroquinone and an alkali metal borohydride. In its adaptation to the dyeing or tinting of hair, the hydroquinones in aqueous solutions may be considered to be leuco-dye compositions. They are applied to the hair and are then, *in situ*, or immediately previously, converted by oxidation to their quinone form, in which form they effectively dye or tint the hair.

Accordingly, the invention also provides a process for the preparation of solutions for the dyeing and tinting of hair which comprises producing and/or stabilizing a hydroquinone by adding to the hydroquinone or to the quinone corresponding thereto in an aqueous medium an amount of alkali metal borohydride such as to maintain the hydroquinone substantially stable and maintaining the pH of the solution above 7. The amount of the alkali metal borohydride, preferably potassium borohydride, is such as to prevent the development of color in the hydroquinone solution, or at least to minimize the development of color in the solution.

To render the solution ready for application as a hair dyeing or tinting preparation, the alkali metal borohydride present in the stabilized hydroquinone solution is preferably destroyed by a reduction of its pH value below pH 7,

2

and this may be done either *in situ* or before application to the hair.

While the solutions are particularly suitable for the dyeing or tinting of hair, their utility is not limited thereto, and they are capable of being satisfactorily applied to the dyeing or tinting of other keratinous material such as wool.

In our copending applications Serial Nos. 401,055 and 401,057 filed January 1, 1953, we have described the use of trihydroxy toluene and trihydroxy benzene, respectively, as agents for the dyeing of keratinous material, the inventions residing in the application of these two trihydroxy aromatic substances to the hair in association with one or more primary aliphatic or aryl aliphatic amines or salts thereof at pH values ranging between 5 and 12.

The present invention may be combined with the inventions of our prior applications, and according to a feature of the present invention, the stabilized hydroquinone solution is admixed with a primary aliphatic or aryl aliphatic amine or salt and is then applied to the keratinous material, e. g., hair, the alkali metal borohydride being destroyed *in situ* or prior to application by adjustment of the pH value of the solution.

The reduction of the quinone compound by the action of the alkali metal borohydride in most instances proceeds readily by the addition of the alkali metal borohydride to an aqueous solution or suspension of the quinone, but with some compounds it has been found an advantage to add alcohol or a small quantity of an alkaline material in order to speed up the rate of reduction. Thus, benzoquinone is readily reduced if first dissolved in alcohol, but reduces only slowly if suspended in water at room temperature. Quinones containing solubilizing substituents, however, will rapidly reduce when the reaction is carried out in water alone; for example, hydroxybenzoquinone is immediately reduced by the action of the potassium borohydride.

Among the various quinones to which the present invention has been applied, there may be mentioned the following: hydroxybenzoquinone, methoxybenzoquinone, 2:aminobenzoquinone, 2:5-bis-diethylaminobenzoquinone, anilinoquinone, 2:5-dihydroxybenzoquinone, 2:5-dimethoxybenzoquinone, chloroquinone, 1:4-naphthoquinone, lawsone, juglone, menaphthone, 2-amino-1:4-naphthoquinone, 1:4-naphthoquinone-4-sulfonate sodium salt, 2:3-dichloro-1:4-naphthoquinone, naphthazarin, indigo, and alizarin.

The invention has been applied with success to hydroxy-naphthoquinones; namely, lawsone, juglone, and naphthazarin. The lawsone and juglone are preferably ground to a fine powder before treatment with the aqueous borohydride solution and then, on mixing with the alkali metal borohydride solution, a rapid reduction occurred. There is a tendency for foaming to occur, and this foaming may be particularly severe when the pH of the solution is reduced in order to destroy any excess of the alkali metal borohydride. The difficulty with foaming is minimized or avoided by carrying out reduction in an aqueous alcoholic medium or by adding an antifoaming agent; for example, the silicone anti-foaming agent sold as "Silicone D. C. Anti-foam A."

Although it is preferable, as pointed out above, to destroy the borohydride by reducing the pH of the composition below pH 7 before application to the hair in order to avoid possible irritation to the skin by the borohydride, dyeing may be successfully carried out even with borohydride present in the composition, in which case, of course, the pH must be at least 7. The color imparted to the hair or other keratinous material may readily be controlled by adjusting the pH of the composition (either before or after destruction of the borohydride) before the composition is applied to the hair. The compositions may

vary from strongly acid to strongly alkaline with resulting variation in the color produced. Extremes of acidity or alkalinity are preferably avoided, particularly when dyeing human hair, in order to avoid possible irritation of the skin. Preferably, the composition when applied to the hair has a pH from about 3 to about 10.

The following examples illustrate the application of the invention to lawsone:

Example 1

1.14 g. of lawsone and 0.70 g. of potassium borohydride were ground together in a mortar and then six portions of this mixture, each of 0.25 g., were weighed into dry test tubes; 5 ml. of water were added and after a few minutes colorless solutions were obtained. Although an appreciable evolution of gas took place, no foam was produced. Subsequently the solutions were treated as follows:

- (i) 3 ml. of 0.5 N hydrochloric acid added and when evolution of gas ceased 5 ml. of water added.
- (ii) 3 ml. of 0.5 N hydrochloric acid added and when evolution of gas ceased 5 ml. of 0.2 M sodium succinate added.
- (iii) 3 ml. of 0.5 N hydrochloric acid added and when evolution of gas ceased 0.75 ml. 0.2 M sodium carbonate and 5 ml. 0.5 M phosphate buffer which had previously been adjusted to pH 8 added.
- (iv) 1.5 ml. 0.5 N hydrochloric acid added and when evolution of gas ceased 5 ml. 0.5 M phosphate buffer at pH 8 added.
- (v) 5 ml. of 0.5 M phosphate buffer at pH 8 added.
- (vi) 3 ml. 0.5 N hydrochloric acid added and when evolution of gas ceased 5 ml. of 0.2 M sodium carbonate added.

A small tress of grey hair and a small square of wool cloth were soaked in each solution for 5 minutes before exposure to the atmosphere for 30 minutes followed by a water rinse and a scour with a detergent.

The dyeing results were similar to those obtained from 1:2:4-trihydroxynaphthalene at the same pH values with the usual intense orange colors from acid solutions. The pH values of the solutions were: (i) 1.8, (ii) 5.7, (iii) 7.4, (iv) 8.5, (v) 9.9, and (vi) 8.9. The presence of the reductant during dyeing (v) did not influence the result. It will be appreciated that the hydroquinone is a dye-precursor which is converted to the dye (hydroxynaphthoquinone) by oxidation in the air.

Example 2

0.36 g. lawsone was ground to an intimate admixture with 0.11 g. of potassium borohydride and was then mixed with 20 ml. water when the solids were taken up into solution.

The solution changed color from deep red to yellow and, on addition of citric acid until the solution just reacted acid, it was found that cloth, and also a tress of grey hair, could satisfactorily be dyed yielding an intense orange coloration.

Example 3

1.14 g. of juglone and 0.70 g. of potassium borohydride were ground together and 0.28 g. samples of the mixture were used for each experiment in the same way as that described in Example 1.

The tendency to foaming was effectively controlled by the addition of a drop of the anti-foaming agent, Silicone D. C. Anti-foam A, referred to above and the pH values of the several solutions were adjusted as in Example 1 and gave values as follows: (i) 2.2, (ii) 6.6, (iii) 8.2, (iv) 9.2, (v) 10.2 and (vi) 9.2.

Example 4

The procedure described in Example 1 was repeated using 1.24 g. of naphthazarin in place of the lawsone and utilizing samples each of 0.30 g. in the same way as in

Example 1 in 50% aqueous alcohol solution instead of aqueous solution.

A dull yellow to green solution was obtained after a short time and the six samples were then adjusted as to their pH as described in Example 1, the six samples having the following pH values: (i) 3.3, (ii) 6.0, (iii) 7.8, (iv) 8.0, (v) 9.8, and (vi) 8.2. On applying the solution to the cloth and hair as previously described, it was found that the shade of dyeing was dependent on the pH of the dye solution, varying from a light red-brown from acid solution to a strong purple to grey on alkaline solution.

Example 5

In this example, 1:2:4-trihydroxybenzene (THB) and mixtures thereof with lawsone were examined; these experiments were carried out by adding powder mixtures of the following composition to 50 ml. of water:

- (a) 0.63 g. THB and 6.75 g. sodium succinate.
- (b) 0.47 g. THB, 0.22 g. lawsone, 0.078 g. potassium borohydride, and 6.75 g. sodium succinate.
- (c) 0.32 g. THB, 0.44 g. lawsone, 0.14 g. potassium borohydride, and 6.75 g. sodium succinate.
- (d) 0.16 g. THB, 0.65 g. lawsone, 0.21 g. potassium borohydride, and 6.75 g. sodium succinate.

Rapid solution and reduction occurred to give colorless solutions and the initial evolution of gas soon subsided due to the rapid destruction of the reducing agent in the presence of the neutral buffer.

Grey hair and cloth were dyed with the solutions to give colors varying from a medium-strong brown to strong orange.

Similar experiments relating to mixtures were carried out with mixtures of lawsone and juglone, juglone and naphthazarin, and with lawsone, juglone, and naphthazarin; in each case the dyes appeared to act additively at pH values ranging from 1.6 to 9.8.

It will be appreciated that the present invention provides an important advance in the dyeing and tinting of hair, in particular rendering it possible to prepare concentrated stable dyeing preparations from the relatively insoluble quinone compounds by converting these quinones to the corresponding hydroquinone and thereafter reoxidizing them, preferably in situ, and preferably with the addition of the primary amines above referred to. Moreover, the use of the borohydride avoids the disadvantages associated with the use of the more usual reducing agents, such as sodium dithionite and stannous chloride, in the treatment of hair.

Variations in the actual dyeing technique may be adopted; for example, instead of or in addition to the use of the above-mentioned amines, oxygen carrier substances may be used; for example, intense dyeing tints may be obtained if a ferrous compound is used as an oxygen carrier.

The solutions for use as dyeing preparations may be made in varying concentrations, thereby rendering possible a close control of the shade to which the keratinous material is dyed.

Although specific embodiments of the invention have been herein described, it is not intended to limit the invention solely thereto, but to include all of the obvious variations and modifications within the spirit and scope of the appended claims.

We claim:

1. A reduced solubilized aqueous quinone dye composition stabilized with a member of the class consisting of sodium and potassium borohydride.
2. The method of making a stable aqueous leuco-dye composition which comprises reacting a quinone with a member of the class consisting of sodium and potassium borohydride in an aqueous medium at a pH of at least 7.
3. An aqueous solution comprising a hydroquinone stabilized with a member of the class consisting of sodium and potassium borohydride, said solution having a pH of at least 7.

4. A stable leuco-dye composition comprising in aqueous solution a hydroquinone and a member of the class consisting of sodium and potassium borohydride at a pH of at least 7.

5. The method of preparing a stable reduced solubilized aqueous solution of a quinone dye which comprises reacting the oxidized form of the dye with a member of the class consisting of sodium and potassium borohydride in an aqueous medium at a pH of at least 7.

6. The method of preparing a stable aqueous solution of a hydroquinone which comprises reacting a quinone with a member of the class consisting of sodium and potassium borohydride in an aqueous medium at a pH of at least 7.

7. The method of dyeing a keratinous material which comprises reducing the oxidized form of a quinone dye with a member of the class consisting of sodium and potassium borohydride in an aqueous medium at a pH of at least 7, and applying said reduced dye to the keratinous material.

8. The method of dyeing hair which comprises reducing a quinone to a hydroquinone by reaction with a member of the class consisting of sodium and potassium borohydride in an aqueous medium at a pH of at least 7, and applying

said aqueous medium containing said hydroquinone to the hair.
